APPARATUS FOR BLANKING AND CEMENTING OFF PERFORATED WELL CASINGS IN A WELL BORE

Reuben C. Baker, Coalinga, and Clarence E. Burt, Los Angeles, Calif., assignors to Baker Oil Tools, Inc., Huntington Park, Calif., a corporation of California

Application November 23, 1935, Serial No. 51,283

8 Claims. (Cl. 166—13)

This invention relates to apparatus for blanking-off sections of perforated casing in an oil well bore.

In some oil fields it is the practice of lining that portion of a well bore extending through a producing zone with perforated or screen casing. For various reasons it becomes sometimes desirable to blank-off all or a portion of such perforated casing and to fill the space between the blanked-off portion of such casing and the well bore with cement to prevent the migration of fluids vertically between the casing and the wall of the hole, and likewise to prevent the entrance of fluid into the casing through the perforations.

It is the principal object of the present invention to provide a simple and very efficient apparatus for use in blanking-off a desired section of perforated well casing while the same is in a well bore, which device being also capable of use in washing out the space exteriorly of the blanked-off casing section, and then filling the same with cement.

One form which the invention may assume is exemplified in the following description and illustrated by way of example in the accompanying drawing, in which:

Fig. 1 is a view in central vertical section through a portion of a well bore in which perforated casing is placed, and showing my improved apparatus positioned therein for operation.

Fig. 2 is a view similar to Fig. 1, showing the apparatus in the position which its parts assume during operation.

Referring more particularly to the accompanying drawing, 10 indicates a well bore and 11 indicates a section of perforated casing therein, which in some fields is used to line the bore where it extends into or through the producing zone. It is sometimes desirable to blank-off either a portion or all of the producing zone, which can be accomplished by the use of my apparatus indicated at 12.

This apparatus comprises an elongated hollow body including a central tube 14 which is fitted at its upper end with a coupling 15. The upper end of this coupling is formed with a female left-hand thread so that it may be connected to the lower end of a running-in tubing 16. The reason for the left-hand thread is so that the running-in tubing 16 may, under some conditions, be disconnected from the coupling 15, when it is desired to leave the apparatus 12 in place in the casing but remove the running-in tubing 16.

The central tube 14 is fitted adjacent its upper

end with an upper head 17, which is welded or otherwise secured to the tubing as indicated. At its lower end the tubing is threaded or otherwise connected to a lower head 18, which is hollow and cylindrical. The length of the central tube 14 is such that it will substantially correspond with the length of the section of perforated casing 11 which it is desired to blank-off.

Securely connected at its upper end to the upper head 17 is an expansible packing sleeve 19 formed of rubber or other suitable elastic material. The lower end of this packing sleeve 19 is securely fastened to the lower end of the lower head member 18. In both instances the ends of the sleeve 19 are secured to the heads 17 and 18 by collars 20 threaded to the heads 17 and 18, forming a water-tight connection therebetween. It will be noticed that the exterior diameters of the collars 20 are just slightly less than the interior diameter of the perforated casing 11, and it will be likewise noticed that when the sleeve 19 is in its normal or collapsed condition, that it is likewise less in external diameter than the internal diameter of the casing 11.

The central tube or fluid conducting member 14 is provided with two radial ports 21 at a point intermediate the upper head 17 and the lower head 18. These ports are controlled by saxophone type spring-pressed check valves 22, which are arranged on the exterior of the tubing so that pressure from within the tubing will open them, but when the pressure within the packing sleeve 19 exteriorly of the tube 14 is greater than the pressure within the tube 14, the valves will be maintained seated.

The valve members 22 have projecting lugs 23 which project inwardly through the ports 21 to a point within the central tube 14. The provision of these lugs enables a spear or other tool, such as indicated in dot and dash lines at 24 in Fig. 2, to be lowered down through the central tube 14 to open the valves 22 and enable the packing sleeve 19 to be collapsed by relieving the pressure therein.

The lower head 18, as previously stated, is hollow and cylindrical and is fitted within its upper end with a bridging valve seat member 25 which is connected with the head member 18 by a shear pin 26. The lower end of the head member 18 is formed with a central back pressure valve port 27 with which a back pressure poppet type valve 28 cooperates. This valve 28 is provided with a stem 29 guided within the head 18 for vertical reciprocation. An expansion spring 30 is provided which engages a spider 31 in the head 18.

at its lower end and a collar 32 at the upper end of the valve stem 29 to constantly tend to maintain the valve 28 seated to prevent the passage of fluid upwardly through the lower head 18. The 5 valve seat member 25 is connected by legs 33 to the collar 32 by means of a shear pin 34.

When the valve seat member 25 is held in place, as illustrated in Fig. 1, it, by its connection with the valve stem 29 through the collar 32, 10 holds the valve member 28 unseated so that fluid may pass upwardly through the head member 18 and upwardly through the central tube 14. This is desirable because it is necessary when lowering the apparatus 12 into the casing to permit fluid 15 already in the bore to pass freely upwardly through the apparatus and through the tubing 16.

To cooperate with the valve seat member 25 is a bridging ball valve member 35 which is not placed in position in the device until after the 20 apparatus is lowered to the point of operation. The ball valve 35 may be dropped down through the running-in tubing 16 so that it may seat on the valve seat member 25 and shut off the passage of fluid downwardly through the tubing 14.

25 In operation of the device, assuming that it is constructed and assembled as illustrated in Fig. 1, it is lowered into the hole, and, as it is lowered down the bore, fluid in the bore may pass upwardly through the apparatus, through the central tube 14 and upwardly through the running-in tubing 16 as it is lowered. The apparatus is lowered to a point where the packing sleeve 19 will register with that section of the perforated 30 casing 11 which it is desired to blank-off. When this point is reached, the ball 35 is dropped into the tubing 16 and caused to lower until it seats on the upper end of the valve seat member 25. Pressure is then built up in the central tube 14 by the pumps connected with the top of the running-in tubing 16.

The pressure which is required to open the valves 22 is less than the pressure required to shear the pin 26 which holds the valve seat member 25 in place. Therefore, the ball valve 35 in 45 cooperating with the seat member 25 effectively shuts off the lower end of the central tube 14. Fluid under pressure is consequently forced outwardly through the valve ports 21 in the central tube 14, and pressure is built up in the chamber 50 between the packing sleeve 19 and the central tube 14 until this sleeve expands into tight engagement with the inner periphery of the perforated casing 11, effectively sealing the perforations 45 therein. The pressure required to effect this seal is less than required to shear the pin 26. However, immediately that a sealing action is effected between the packing sleeve 19 and the perforated casing 11, the pressure is built up to a point where it shears the pin 26, thus rendering 60 the bridging valve mechanism at the lower end of the central tube 14 ineffective, because the valve seat member 25 is lowered to a point where the ball valve 35 is no longer effective. This is illustrated in Fig. 2. At the same time, the shear pin 34, which connects the valve seat member 25 to the collar 32 on the upper end of the valve stem 29, is sheared releasing the valve member 28 and permitting the same to close. However, the fluid pressure pumped downwardly through 65 the tubing 16 is sufficient to open the valve 28 to maintain circulation. However, when the pressure within the tubing 16 drops, the pressure in the bore, in conjunction with the spring 30, seats the valve 28, preventing the passage of fluid upwardly through the lower head 18.

If it is merely desired to blank-off the casing, the tubing 16 may then be revolved in a left-hand direction, disconnecting it from the coupling 15, thus permitting the tubing 16 to be removed from the bore. Inasmuch as the valves 22 will be 5 closed, the pressure interiorly of the packing sleeve 19 will be sufficient to maintain the seal.

However, it may be desired to cement off that section of the perforated casing with which the apparatus is aligned. In such an instance the 10 tubing 16 is not disconnected from the coupling 15 until the cementing operation is complete. In such an instance washing fluid is first pumped downwardly through the tubing 16, downwardly through the central tube 14 and the head member 18 and out of the valve port 27 in the lower end of the head member 18. This fluid will pass out of perforations below the head member 18, and then upwardly between the exterior of the 20 perforated casing 11 and the wall of the hole, gaining entrance back into the casing through perforations therein above the apparatus 12, thus washing the mud out of this space and preparing this space for cementing. Cement slurry under pressure is then forced downwardly 25 through the tubing 16 downwardly through the apparatus, and it will follow the same path as the washing fluid. Sufficient cement is pumped downwardly in this manner until the area between the blanked-off section and the wall of the 30 hole is filled with cement. The tubing 16 is then disconnected from the coupling 15, as described, and washed out and removed from the bore.

If it is desired, however, to remove the apparatus after the cementing operation, a tool such as indicated at 24 in Fig. 2 may be lowered down 35 through the tubing to open the valves 22, collapsing the packing sleeve 19; then the entire apparatus may be removed upwardly from the casing. The removal, however, will unaffect the 40 cement, due to the fact that it will already have set and will act to blank-off the perforated casing 11.

When the apparatus is used to wash out and 45 cement casing, a bridge may be formed in any preferred manner in the perforated casing 11 below the point where the lower head 18 of the apparatus will be positioned. Likewise, a circulating jar of any preferred design may be incorporated in the running-in tubing 16 to enable the 50 latter to be washed out immediately following cementing.

From the foregoing it is obvious that we have 55 provided a comparatively simple apparatus which may be used in blanking-off perforated casing while the same is in a well bore, and which also may be used in washing out the space between such blanked off area and the well bore and filling such space with cement.

While we have shown the preferred form of our 60 invention, it is to be understood that various changes may be made in its construction by those skilled in the art without departing from the spirit of the invention as defined in the appended claims.

Having thus described our invention, what we 65 claim and desire to secure by Letters Patent is:

1. An apparatus of the character described comprising an elongated hollow body adapted to be connected at its upper end to a string of running-in tubing, an expandable packing sleeve concentrically arranged about said body and connected in a fluid-tight manner at its ends to said body, check valve means in said body at a point intermediate the ends of said sleeve to enable 70

fluid to be forced from said body between said body and said sleeve, means in said body below said check valve means preventing the passage of fluid downwardly through said body, said latter-named means being capable of being rendered ineffective by fluid pressure within the body above that required to open said check valve means.

2. An apparatus of the character described comprising an elongated hollow body adapted to be detachably connected at its upper end to a string of running in tubing, an elongated expansible packing sleeve of a diameter greater than the diameter of the central portion of said body, said sleeve being arranged concentrically on said body, a fluid-tight connection between the ends of said sleeve and said body, said body having valve ports formed therein at a point between the ends of the sleeve whereby fluid from within the body may pass into the space between the sleeve and the exterior of the body to expand the sleeve, check valves normally preventing the return of fluid from between the sleeve and the body into said body, bridging valve means in the body below said ports to interrupt the flow of fluid through the body, said bridging valve means capable of being rendered ineffective by fluid pressure within the body, the pressure required to render said bridging valve means ineffective being greater than required to open said check valves and expand said sleeve.

3. An apparatus of the character described comprising an elongated hollow body adapted to be detachably connected at its upper end to a string of running in tubing, an elongated expansible packing sleeve of a diameter greater than the diameter of the central portion of said body, said sleeve being arranged concentrically on said body, a fluid-tight connection between the ends of said sleeve and said body, said body having valve ports formed therein at a point between the ends of the sleeve whereby fluid from within the body may pass into the space between the sleeve and the exterior of the body to expand the sleeve, check valves normally preventing the return of fluid from between the sleeve and the body into said body, the lower end of said body being formed with a valve port, a back pressure valve normally controlling said port, bridging valve means in said body between said back pressure valve and said check valves normally preventing the passage of fluid downwardly through the body, said bridging valve means capable of being rendered ineffective by fluid pressure within the body above the same, the fluid pressure to render the said bridging valve means ineffective being considerably greater than that required to open said check valves and expand said sleeve.

4. An apparatus of the character described comprising an elongated hollow body adapted to be detachably connected at its upper end to a string of running in tubing, an elongated expansible packing sleeve of a diameter greater than the diameter of the central portion of said body, said sleeve being arranged concentrically on said body, a fluid-tight connection between the ends of said sleeve and said body, said body having valve ports formed therein at a point between the ends of the sleeve whereby fluid from within the body may pass into the space between the sleeve and the exterior of the body to expand the sleeve, check valves normally preventing the return of fluid from between the sleeve and the body into said body, the lower end of said body being formed with a valve port, a back pressure valve normally controlling said port, bridging

valve means in said body between said back pressure valve and said check valves normally preventing the passage of fluid downwardly through the body, said bridging valve means capable of being rendered ineffective by fluid pressure within the body above the same, the fluid pressure to render the said bridging valve means ineffective being considerably greater than that required to open said check valves and expand said sleeve, a connection between said bridging valve means and said back pressure valve holding said back pressure valve open, said connection being disrupted when said bridging valve means is rendered ineffective.

5. An apparatus of the character described comprising an elongated hollow body adapted to be connected at its upper end to a string of running in tubing, an expansible packing sleeve concentrically arranged about said body and connected in a fluid-tight manner at its ends to said body, check valve means in said body at a point intermediate the ends of said sleeve to enable fluid to be forced from said body between said body and said sleeve, means in said body below said check valve means preventing the passage of fluid downwardly through the lower end of the body until the fluid pressure in the body exceeds that necessary to open said check valve means and expand said sleeve.

6. An apparatus of the character described comprising a center tube adapted to be connected to the lower end of a string of running in tubing, an upper and a lower head member connected with said tube, back pressure valve means in the lower head member to permit fluid to be pumped downwardly through said tube and head member but not in the opposite direction, an expansible sleeve arranged concentrically about said center tube and connected at its ends in a fluid-tight manner to said head members, said center tube having ports formed therein between said head members to enable fluid to be pumped in the space between said tube and said sleeve to expand the latter, check valve means controlling said ports to prevent the back flow of fluid into the body, and bridging valve means between said back pressure valve and said valve ports to prevent the flow of fluid downwardly through said tube until the fluid pressure in the tube reaches a point exceeding that required to open said check valve means and expand said sleeve.

7. An apparatus of the character described comprising a center tube adapted to be connected to the lower end of a string of running in tubing, an upper and a lower head member connected with said tube, back pressure valve means in the lower head member to permit fluid to be pumped downwardly through said tube and head member but not in the opposite direction, an expansible sleeve arranged concentrically about said center tube and connected at its ends in a fluid-tight manner to said head members, said center tube having ports formed therein between said head members to enable fluid to be pumped in the space between said tube and said sleeve to expand the latter, check valve means controlling said ports to prevent the back flow of fluid into the body, and means for opening said check valve means from within said body.

8. An apparatus of the character described comprising a center tube adapted to be connected to the lower end of a string of running in tubing, an upper and a lower head member connected with said tube, back pressure valve means in the lower head member to permit fluid to be pumped

downwardly through said tube and head member but not in the opposite direction, an expandible sleeve arranged concentrically about said center tube and connected at its ends in a fluid-tight manner to said head members, said center tube having ports formed therein between said head members to enable fluid to be pumped in the space between said tube and said sleeve to expand the latter, check valve means controlling said 10 ports to prevent the back flow of fluid into the

body, bridging valve means between said back pressure valve and said valve ports to prevent the flow of fluid downwardly through said tube until the fluid pressure in the tube reaches a predetermined point above that required to open said check valve means and expand said sleeve, and means for opening said check valve means from within said body to relieve said pressure.
